[57] CLAIM

The ornamental design for a material spreader and distributor, as shown and described.

DESCRIPTION

FIG. 1 is a perspective view of a material spreader and distributor showing our new design;

FIG. 2 is an enlarged fragmentary side elevational view thereof of the side opposite that shown in FIG. 1, it being understood that the handle is shown in an alternate position and has been broken away for convenience of illustration;

FIG. 3 is an enlarged side elevational view thereof of the side shown in FIG. 1; and

FIG. 4 is an enlarged bottom plan view thereof, it being understood that the top is substantially a mirror image of the bottom.

The handle has been broken away in the center in FIGS. 1, 3 and 4 to indicate indeterminate length.
